OUTPUT VOLTAGE CONTROL FOR A BATTERY

Sterling W. Backler, Rte. 1, Fredericktown, Mo. 63645

Filed June 22, 1967, Ser. No. 7,555

Term of patent 14 years

(Cl. D26—1)

FIG.1

FIG. 2

FIG. 3

FIG. 5

FIG. 4

FIG. 1 is a top view of an output voltage control for a battery showing my new design.

FIG. 2 is a side view of the device.

FIG. 3 is a bottom view of the device.

FIG. 4 is an end view of the device.

FIG. 5 is a vertical sectional view of the device taken along line 5—5 of FIG. 1.

The opposite side and end are mirror images of those illustrated in FIGS. 2 and 4 respectively.

I claim:

The ornamental design for an output voltage control for a battery, substantially as shown and described.
